UNITED STATES PATENT OFFICE.

HENRY GAU, OF PIERZ, MINNESOTA.

MEANS FOR AUTOMATICALLY UNLOCKING DOORS OR GATES.

1,148,161.

Specification of Letters Patent. Patented July 27, 1915.

Application filed September 8, 1914. Serial No. 360,781.

To all whom it may concern:

Be it known that I, HENRY GAU, a citizen of the United States, and a resident of Pierz, in the county of Morrison and State of Minnesota, have invented new and useful Improvements in Means for Automatically Unlocking Doors or Gates, of which the following is a specification.

My invention relates to gates or doors, and 10 pertains more particularly to gates or doors that are automatically opened by the approach of a vehicle.

The object of my invention is to produce a vertically movable gate or door, which is 15 normally held closed by a latch at its base, provided with a suitable counter weight for raising same when the latch is released, and a pivoted platform adjacent the gate connected with said latch adapted to release the 20 latch by being depressed by the weight of an approaching vehicle.

To these ends, my invention includes the combination and arrangement of component parts to be hereinafter described and more 25 particularly pointed out in the claim.

In the accompanying drawings, in which like reference characters indicate similar parts, Figure 1 is a perspective view of my invention; Fig. 2 is a vertical sectional view 30 thereof taken on the line 2—2 Fig. 1, and Fig. 3 is a transverse sectional view of the same taken on the line 3—3 of Fig. 1.

Referring now to the drawings, 1 indicates the base frame or foundation of my gate 35 structure forming the walls of the well 2 in which, beneath the platform 3 covering same, is carried the latch and operating mechanism hereinafter described. The vertical frame 4 is mounted on said base, and comprises the 40 upright members 5 and 6 and cross pieces 7 and 8 connecting same. The opposite inner faces of the upright members are provided with tracks 9 and 10 in which the door or gate 11 is slidably mounted. Said gate is 45 raised and opened by the weights 13 and 14 carried on the cords 15 and 16, the opposite ends of which are attached to the top of the gate, and pass over blocks 17 and 18 journaled in the upright members 5 and 6 a suitable 50 distance above the top of the gate.

For the purpose of holding the gate normally closed, I provide a latch 19 pivotally mounted in the platform on the innerside of the gate. Said latch comprises the shank 19'

pivoted at *a* intermediate its ends, having the 55 engaging head 19^a on its outer end adapted to engage the projection *b* on the door, and the depending portion *c* having an eyelet *e* adjacent its end. Said latch is held in normal engagement with the projection *b* of the 60 door by the coil spring 20 attached at one end to the lower portion of the latch and at its opposite end to the adjacent wall of the base frame.

To release the door and permit it to rise 65 and open, I provide a hinged section 21 of the platform having a depending arm 22, at the lower end of which is pivotally attached the rod 23, which at its opposite end is connected with the depending portion *c* of the 70 latch through the eyelet *e*. The tension of the spring 20 normally holds the head of the latch in engagement with the projection on the door, and also holds the hinged section 21 of the platform slightly raised at its free 75 edge; and it will be apparent that said hinged section will be depressed by the weight of an approaching vehicle passing over same, which moves the arm 22 downwardly and through the rod 23 disengages 80 the latch from the door when it is raised by the weights 13 and 14.

Grips 24 adjacent the base of the door are provided for conveniently lowering and closing same.

Having thus described my invention, what I claim as new and desire to be secured by Letters Patent, is—

The combination with a sliding door having a catch adjacent to its lower edge, of a 90 spring-pressed latch comprising a shank pivoted intermediate its ends having an engaging head on its outer end for normally engaging said catch to hold the door closed, and a depending portion, a platform adjacent to said door having a section thereof hinged at one edge and being free at its opposite edge, a depending arm carried on the lower face of the hinged section adjacent to its free edge, and a link connecting said arm 95 with said depending portion of the latch to release the latch head by the depression of the free end of said hinged section of the platform, substantially as described.

HENRY GAU.
